(57) **CLAIM**

The ornamental design for a extruder die insert, as shown and described.

DESCRIPTION

FIG. 1 is a top perspective view of the first embodiment of the extruder die insert of the present invention;

FIG. 2 is a top plan view of the first embodiment of the extruder die insert of the present invention;

FIG. 3 is a front elevation view of the first embodiment of the extruder die insert of the present invention, with the right elevation view, left elevation view, and rear elevation view all mirror images of the front elevation view;

FIG. 4 is a top perspective view of the second embodiment of the extruder die insert of the present invention;

FIG. 5 is a top plan view of the second embodiment of the extruder die insert of the present invention; and,

FIG. 6 is a front elevation view of the second embodiment of the extruder die insert of the present invention, with the right elevation view, left elevation view, and rear elevation view all mirror images of the front elevation view.

The broken line shown on FIGS. 1, 3, 4, and 6 defines the bounds of the claimed design and forms no part thereof.
